UNITED STATES PATENT OFFICE

2,352,997

STAPLING DEVICE

Max Vogel, Bridgeport, Conn., assignor to Neva-Clog Products, Inc., Bridgeport, Conn., a corporation of Connecticut

Application October 18, 1941, Serial No. 415,527

6 Claims. (Cl. 1—49)

The present invention relates to improvements in stapling devices, particularly of the type adapted to separate individual staples from a staple strip and drive and clinch the staples with respect to the material to be stapled. Such stapling devices may be either of the plier or desk type, although the device illustrated herein is of the stapling plier type, it being understood that the particular features of novelty of the present invention are applicable to either type. In the operation of stapling devices of this character staples sometimes become jammed in the staple driving passage, this condition usually resulting from attempting to drive the staples through impenetrable material, and with the usual construction of stapling devices the interior structure is so concealed and permanently connected that it is difficult to clear the jammed staples, or to repair or replace the parts if they become damaged.

Stapling devices have been constructed in the past in which a movable front wall has been provided which could be raised to enclose the staple driving passage, but these have been objectionable due to the fact that the spring pressure exerted upon the staple strip by the push shoe would cause the staple strip to be forcefully projected from the forward end of the device upon opening of the front wall with the chance of causing injury to the person handling the device. Safety catch means have been provided for the purpose of preventing the forward projection of the staple strip, but these have been objectionable due to the fact that the actuating means therefor was so exposed that it could be unintentionally operated by touching it.

It is an object of the present invention to provide a stapling device having a slidable front wall or closure member which may be readily moved to open position to expose the forward end of the staple guide and drive passage, in combination with automatic catch means for preventing forward projection of the staple strip under spring pressure and forward removal thereof in the open position of the closure member, and to provide such catch means which will yield inwardly upon insertion of a tool from the forward end, so that this tool may be passed entirely through the staple guide passage to remove the staples in a rearward direction. It is a further object to provide a movable closure member which is adapted to be automatically moved to its closed position upon operation of the staple driving means to drive a staple to

move the catch mechanism to its normal inoperative or non-obstructing position.

A further object is to provide an improved construction of a staple driving head in which the various parts are assembled in interlocking relation without the use of rivets, welding or other such permanent assembling means, enabling the device to be readily disassembled and reassembled for the purpose of convenient assembly and repair or replacement of any of its parts.

Another object is to provide improved push shoe means of simple and inexpensive construction, and particularly a push shoe member formed of a single piece of sheet metal, and a push shoe and spring mounting guide rod and handle, formed of a single piece of wire.

With the above and other objects in view an embodiment of the invention is shown in the accompanying drawings, and this embodiment will be hereinafter more fully described with reference thereto, and the invention will be finally pointed out in the claims.

In the drawings:

Fig. 1 is a side elevation of a stapling plier, according to the illustrated exemplary embodiment of the invention.

Fig. 2 is a rear elevation thereof.

Fig. 3 is an enlarged side elevation of the staple driving head portion of the stapling plier, a portion of the housing being broken away.

Fig. 4 is a front elevation of the stapling plier, partially broken away.

Fig. 5 is a vertical transverse sectional view, looking forwardly, taken along the line 5—5 of Fig. 3.

Fig. 6 is a horizontal sectional plan view, the staple driving head being shown in top plan and the housing being shown in horizontal section along the line 6—6 of Fig. 3.

Fig. 7 is a vertical transverse sectional view, looking toward the rear, taken along the line 7—7 of Fig. 3.

Fig. 8 is a vertical longitudinal sectional view taken along the line 8—8 of Fig. 5.

Fig. 9 is a plan view of the push shoe and rod, the rod being broken away at its intermediate portion.

Fig. 10 is a front elevation, partially broken away, showing the front wall member in its raised position to expose the staple guide and drive passages.

Fig. 11 is a side elevation with the front wall member in the raised position illustrated in Fig. 10, portions of the various parts being broken away along all offset lines.

Fig. 12 is a respective view showing the several parts of the staple driving head and a portion of the housing in separated relation.

Similar reference characters indicate corresponding parts throughout the several figures in the drawings.

Referring to the drawings, the stapling plier, according to the exemplary illustrated embodiment of the invention, comprises a housing 10, preferably formed of sheet metal pressed and bent to shape, having the upper grip handle 11 formed integrally therewith, the lower portions of the side walls of the housing having slots 12 constituting the receiving mouth for material to be stapled. The portions 13 of the side walls below these slots have a U-shaped strut member 14 secured therein, preferably by means of welding, its transverse portion forming the lower wall of the housing. Within the strut member there is welded or otherwise suitably secured an anvil member 15 having at its forward end an upwardly offset portion 16 having anvil recesses 17 formed therein, and having at its rearward end an upwardly bent wall 18 with which the spring of the plier is adapted to be hooked, as will presently more fully appear.

The staple driving head and staple carrying guide of the plier, which constitutes the upper jaw for cooperating with the lower anvil jaw, is of box-like form and comprises a member 19 of U-shape in cross-section having a rearwardly extending elongated channel extension portion 20 for receiving the staple strip carrier bar and staple push shoe, the member 19 which extends vertically from the forward end of the extension portion 20 constituting the side wall portions of the staple driving head, between which the inner frame member is interlockingly engaged, as will hereinafter more fully appear.

Inwardly bent horizontally disposed flanges 21-21 are provided along the upper edges of the side walls of the extension portion 20 and form an upper staple strip guide or limit means for the staple strip and push shoe, slidably mounted upon the staple carrier bar or rail 22 which is secured to the base of the member 19 and its extension portion 20, preferably by welding. This staple carrier bar 22 is of U-shape in cross section and is closed at its forward end by means of a front wall portion 23, bent upwardly from its base portion against the forward vertical edges of its side walls. The side walls of the staple carrier bar are inwardly spaced from the side walls of the member 19 and its extension portion 20, and the top edges of the side walls are spaced downwardly beneath the flanges 21-21, thereby providing rectangular guide spaces at each side in which the inverted U-shaped staple strip A is guided. The forward surface of the front wall portion 23 is inwardly offset from the forward edges of the member 19 a distance substantially corresponding to the thickness of the individual staples to provide a staple driving space between the side walls of the member 19.

Intermediate the ends of the extension portion 20 its base is transversely slotted, as at 24, and ears 25-25 extend downwardly in flush relation with the side surfaces of the extension portion 20, these ears being provided with aligned apertures 26-26 which are engaged by the pin 27, mounted in the sides of the housing 10 at a point near its lower edges rearwardly of the notches 12-12, the side surfaces of the extension 20 and the ears 25-25 being spaced from the inner surfaces of the sides of the housing 10 a sufficient

distance to receive the sides of the staple driver operating lever, hereinafter more fully described. The pin 27 is preferably of a type having a fixed head 28 at one end and a shouldered screw-threaded stud portion 30 at its other end upon which is screwed a circular nut 31.

Clearance slots 32-32 are provided at the forward end of the base of the member 19 at each side of the staple carrier bar being of a length sufficient to permit the legs of a staple to pass through with the staple in a horizontal position. This prevents jamming of a staple which may be inadvertently driven while in a horizontal position, and as may occur when the push shoe is temporarily removed and a single staple is in the staple driving passage.

Within the member 19 there is interlockingly engaged between its side walls an inverted U-shaped frame member 33, the upper transverse portion of which constitutes the top wall of the head. The sides of this frame member are provided at their lower ends with inwardly bent flanges 34-34, which are in line with the inwardly bent flanges 21-21 provided at the upper edges of the side walls of the extension 20, and constitute therewith an upper staple strip guide or limit means extending from the forward ends of the flanges 21 to the staple driving passage.

The frame member 33 is provided upon its side walls with outwardly pressed studs 35, preferably two at each side in diagonal arrangement, and which interlockingly engage holes 36 correspondingly placed in the side walls of the member 19, these side walls of the member 19 being adapted to be sprung apart slightly to permit the frame members to be slid into place, whereupon the studs 35 snap into position in the holes 36. The diagonal arrangement of the studs prevents improper assembly, as the studs 35 will not register with the holes 36 except in the one proper position of the frame member. The frame member is rendered rigid against collapse of its side walls toward each other by means of a cross pin 37 having its reduced shouldered ends 38 staked into apertures 39 in the side walls, this pin also providing a pivotal support for the safety latch member, presently to be more fully described.

In the assembled relation of the frame member its forward edge is inwardly offset from the forward edges of the side walls of the member 19 to provide a guide space for the staple driver plate 40 which slidably fits into the recessed space thus provided, with its inner surface engaging the forward edges of the frame member 33 and its side edges engaging the inner surfaces of the side walls of the member 19. The forward surface of the staple driving plate is substantially flush with the forward edges of the side walls of the member 19 and is engaged by the forward portion of the vertically movable closure sleeve member, presently to be more fully described, this sleeve member also enclosing the side walls of the member 19, to prevent outward springing of the side walls and thus positively lock the frame member 33 in its assembled position. The staple driver plate 40 is provided with a rectangular slot 41 in which the end of the staple driver operating lever is engaged.

The closure sleeve member 42 comprises a front wall portion 43, side wall portions 44-44 bent rearwardly from the front wall portion and having rectangular cut-out formations 45-45 at their upper edges forming side flanges for the upper portion of the front wall, which extends upwardly with respect to the upper edges of the

side walls, the upper end of the front wall 43 having a rearwardly bent top flange portion 46 having its rear edge flush with the vertical edges of the cut-out formation 45. The side walls are provided at their rearward edges with inwardly bent flanges 47 and 48 respectively, the flange 47 being provided at its upper portion with an extension latch operating portion 49. The upper edges of the flanges 47 and 48 are flush with the upper edges of the side walls 44—44 while the lower edges of the flanges are upwardly spaced from the lower edges of the side walls so that in the assembled relation upon the head the flanges clear the extension portion 20 of the head. In the front wall 43 there is provided a vertically disposed slot 50 adapt to be engaged by the end of the staple driver operating lever, presently to be more fully described, and which is of sufficient length to permit of the movement of the lever in its staple driving operation. Below the slot 50 there is provided an outwardly embossed shoulder formation 51 for the purpose of providing an abutment for engagement of a finger or a suitable tool to actuate the closure sleeve member upwardly to its open position.

The closure sleeve member 42 is assembled with the head by sliding it downwardly thereon over the assembled head member 19, frame member 33, and staple driving plate 40, the side walls 44 enclosing the side walls of the head 19, the front wall 43 enclosing the forward edges of the side walls 19 and the staple driving plate 40, thus constituting the forward wall of the staple driving plate passage or slide-way of the head, and the flanges 47 and 48 extending over the rearward edges of the side walls of the frame 33.

In the assembled relation with the body the top flange 46 fits into a recess 52 provided in the forward edge of the top wall of the body and which permits the closure sleeve to be raised to its open position, as indicated in Figs. 10 and 11, this raised position being limited by abutment of the lower end of the slot 50 with the end of the staple driver operating lever.

The staple driver operation lever is of sheet metal, formed and bent to shape, and comprises a lower grip handle portion 53 from which the spaced side portions 54—54 are bent upwardly in spaced relation and are then bent inwardly, as at 55, the side portions which then extend upwardly and forwardly being brought into contacting relation and welded together to form a forwardly projecting arm 56 of double metal thickness. This arm 56 is pivotally mounted within the housing 10 upon a pin 57 extending between the side walls of the housing, this pin preferably being of a type similar to the pin 27, including a fixed head 58 at one end and a shouldered threaded stud portion 59 at its other end upon which a circular nut 60 is screwed, this construction permitting of the convenient assembling and disassembling of the plier. The lower edge of the arm 56 is conveniently made of stepped formation, and the forward reduced-height end portion is engaged with the slot 41 of the staple driver plate 40 and the slot 50 of the closure sleeve member, being of a height corresponding to the length of the slot 41 so that movement of the lever in the slot 50 imparts movement to the plate 40 to depress and retract it.

It will be observed that the staple driver operating lever arm 56 extends between the flanges 47 and 48 of the closure sleeve 42, and that the extension portion 49 of the flange 47 extends to the surface of the arm, for the purpose of pro-

viding an actuating means for the safety catch member, presently to be more fully described.

Upon pressing the handles 11 and 53 together the operating lever pivots about the pin 57 and the side portions 54—54 thereof move slidably between the extension 20 and the side walls of the housing 10, being provided for this purpose with slots 61—61 arranged concentrically to the axis of the pin 57 and engaged by the pin 27.

10 A spring 62, coiled intermediate its ends, has one end provided with a hook 63 hooked over the wall portion 18 of the lower jaw, its other end being slidably engaged with the inner surface of the handle 53, and its coil being disposed rearwardly of the pin 27 and pressed upwardly against the under surface of the extension 20, this single spring thus exerting pressure to both press the handle 53 to open position and to normally exert pressure upon the staple driving head and extension portion 20 in counter-clockwise direction.

25 The safety catch member 64 is pivotally mounted upon the pin 37 of the frame member 33, being provided at its lower end with a rearwardly facing hook-shaped tooth portion 65 normally disposed in the space between the flanges 34—34 in spaced relation above the staple guide passage of the bar 22, and provided at its upper rearward edge portion with an angularly bent flange 66, the edge of this flange adapted to engage the catch operating portion 49 of the closure sleeve member, and being provided at its lower end with a rounded nose portion 67 which engages the portion 49 in the normal operating position of the pliers. A spring 68 is coiled about the pin 37 and has one end engaged with a retaining lug 69 formed in one side wall of the frame member 33 and its other end engaged with a retaining lug 70 formed in the safety catch member 64, this spring exerting pressure upon the safety catch member in clockwise relation to yieldably press the edge of the flange 66 against the portion 49. In the raised position of the closure sleeve member to expose the forward end of the staple guide and

45 drive passage the safety catch member moves in clockwise direction as the portion 49 moves upwardly along the flange 66, causing the tooth end 65 to swing downwardly into the staple guide passage, and thus provide a stop to prevent forward movement of the staples. The staples are thus prevented from being projected from the forward end of the guide passage under the pressure of the push shoe when the closure sleeve is moved to open position. In the open position, as shown clearly in Figs. 9 and 10, the catch member positively prevents any forward movement of staples which may remain upon the bar or rail 22 rearwardly of the catch member, and also prevents forward movement of the push shoe, this being 50 due to the fact that the clockwise movement of the catch member is positively limited by the portion 49. However, the catch member will yield in counter-clockwise direction, so that it is possible to insert a tool through the staple guide passages from front to rear, the tool engaging the tooth end of the catch member projecting in the staple guide passage and swinging it clear the passage against the pressure of the spring 68. As soon as the tool is withdrawn the catch member 55 will swing into the staple guide passage.

60 The staple carrying bar is provided with a push shoe 71 of inverted U-shape in cross-section, pressed forwardly by a spring 72 disposed upon a rod 73 slidably engaged with a pair of downwardly bent apertured guide lugs 74 and 75, this

rod having an abutment head 76 formed upon its forward end to limit the forward movement of the push shoe under the pressure of the spring, when the push shoe and rod are removed from the plier. The transverse portion of the shoe is provided with downwardly bent lugs 77, spaced rearwardly from the forward edge a distance corresponding to the thickness of the forward wall 23 of the staple carrying bar, so that when the last staple of the strip has been driven the push shoe will be prevented from entering the staple driving passage, the lugs abutting the inner surface of the wall 23 with the forward edge of the push shoe flush with the forward surface of the front wall 23.

The rod 73 is provided at its rearward end with a handle portion 78 bent to shape, being in the form of a triangular loop having the inner end of the loop brought together and secured by welding. The extremity of the rod is bent outwardly from the inner end of the loop to provide a retaining lug 79, which is adapted to be detachably latched through rotation of the rod in a shouldered notch 80 provided in one side wall of the extension portion 20, the shoulder in this notch projecting rearwardly so that upon slight forward movement of the rod against the pressure of the spring 72 the lug will disengage from the shoulder and permit turning movement of the rod out of engagement therewith, whereupon the push shoe may be withdrawn from the staple guide bar or rail.

In loading the device with a new staple strip the strip is inserted from the rear, with the push shoe removed, the push shoe being thereupon slid into place.

I have illustrated and described a preferred and satisfactory embodiment of my invention, but it will be understood that changes may be made therein, within the spirit and scope thereof, as defined in the appended claims.

Having thus described my invention what I claim and desire to secure by Letters Patent is:

1. In a stapling device, a staple driving head including a staple driving passage and staple strip supporting means adapted to guide individual staples of a staple strip into said passage, a staple driver engaged in said passage for reciprocatory staple driving and retracting movement, a closure member movably mounted on said head for opening and closing movement to respectively open and close the forward side of said staple driving passage, a catch member pivotally mounted in said staple head above said staple strip supporting means including a catch portion normally disposed in spaced relation above the staple strip supported upon said supporting means and adapted through pivotal movement of said catch member in one direction to move in an arc forwardly into blocking engagement with said strip to block the forward movement thereof toward said staple driving passage, and catch actuating means carried by said movable closure member adapted through the opening movement thereof to effect forward movement of said catch portion of said catch member to blocking position and including a part arranged to engage said catch member and positively block further forward movement, and said catch actuating means adapted through the closing movement of said closure member to effect movement of said catch portion of said catch member to its normal non-blocking position.

2. In a stapling device, a staple driving head including a staple driving passage and staple strip

supporting means adapted to guide individual staples of a staple strip into said passage, a staple driver engaged in said passage for reciprocatory staple driving and retracting movement, a closure member movably mounted on said head for vertical reciprocatory opening and closing movement to respectively open and close the forward side of said staple driving passage, a catch member pivotally mounted in said staple head above said staple strip supporting means including a catch portion normally disposed in spaced relation above the staple strip supported upon said supporting means and adapted through pivotal movement of said catch member in one direction to move into blocking engagement with said strip to block the forward movement thereof toward said staple driving passage, and catch actuating means carried by said movable closure member adapted through the vertical reciprocatory opening movement thereof to effect movement of said catch member to blocking position and through the closing movement to effect movement of said catch member to its normal non-blocking position.

3. In a stapling device, a staple driving head including a staple driving passage and staple strip supporting means adapted to guide individual staples of a staple strip into said passage, a staple driver engaged in said passage for reciprocatory staple driving and retracting movement, a closure member movably mounted on said head for vertical reciprocatory opening and closing movement to respectively open and close the forward side of said staple driving passage, a catch member mounted in said staple head above said staple strip supporting means including a catch portion normally disposed in spaced relation above the staple strip supported upon said supporting means and adapted through movement of said catch member in one direction to move into blocking engagement with said strip to block the forward movement thereof toward said staple driving passage, and catch actuating means carried by said movable closure member and engageable with said catch member adapted through the vertical reciprocatory opening movement thereof to effect movement of said catch member to blocking position and through the closing movement to effect movement of said catch member to its normal non-blocking position.

4. In a stapling device, a staple driving head including a staple driving passage and staple strip supporting means adapted to guide individual staples of a staple strip into said passage, a staple driver engaged in said passage for reciprocatory staple driving and retracting movement, a closure member movably mounted on said head for opening and closing movement to respectively open and close the forward side of said staple driving passage, a catch member movably mounted in said staple head above said staple strip supporting means including a catch portion normally disposed in spaced relation above the staple strip supported upon said supporting means and adapted through movement of said catch member in one direction to move in an arc forwardly into blocking engagement with said strip to block the forward movement thereof toward said staple driving passage, and catch actuating means carried by said movable closure member adapted through the opening movement thereof to effect forward movement of said catch portion of said catch member.

member to blocking position and including a part arranged to engage said catch member and positively block further forward movement, and said catch actuating means adapted through the closing movement of said closure member to effect movement of said catch portion of said catch member to its normal non-blocking position, and spring means cooperating with said catch member exerting pressure thereon to move it to its blocking position, said catch member adapted to be moved to a non-blocking position through pressure exerted thereon through contact with its catch portion when the closure member is in its open position.

5. In a stapling device, a staple driving head including a staple driving passage and staple strip supporting means adapted to guide individual staples of a staple strip into said passage, a staple driver engaged in said passage for reciprocatory staple driving and retracting movement, a closure member movably mounted on said head for opening and closing movement to respectively open and close the forward side of said staple driving passage, a catch member pivotally mounted in said staple head above said staple strip supporting means including a catch portion at one side of its pivotal axis normally disposed in spaced relation above the staple strip supported upon said supporting means and adapted through pivotal movement of said catch member in one direction to move in an arc forwardly into blocking engagement with said strip to block the forward movement thereof toward said staple driving passage, and a camming portion at the other side of its pivotal axis, catch actuating means carried by said movable closure member engaged with said camming portion adapted through the opening movement thereof to effect forward movement of said catch portion of said catch member to blocking position and to positively block further forward movement, said catch actuating means adapted through closing movement of said closure member to effect movement of said catch portion of said catch member to its

normal non-blocking position, and spring means cooperating with said catch member exerting pressure thereon to yieldably engage said camming portion with said catch actuating means, 5 said catch member adapted to be moved to non-blocking position independently of movement of said closure member through pressure exerted thereon through contact with its catch portion when the closure member is in its open position.

10 6. In a stapling device, a staple driving head including a staple driving passage and staple strip supporting means adapted to guide individual staples of a staple strip into said passage, a staple driver engaged in said passage for reciprocatory staple driving and retracting movement, a staple driver actuating lever engaged with said staple driver and projecting forwardly therefrom, a closure member movably mounted on said head for reciprocatory opening and closing movement to respectively open and close the forward side of said staple driving passage, and having a slot engaged by the forwardly projecting end of said lever, a catch member pivotally mounted in said staple head above said staple strip supporting 15 means including a catch portion normally disposed in spaced relation above the staple strip supported upon said supporting means and adapted through pivotal movement of said catch member to move into blocking engagement with such strip to block the forward movement thereof toward said staple driving passage, and means carried by said movable closure member adapted through the opening movement thereof to effect movement of said catch member to blocking position and through closing movement to effect movement of said catch member to its normal non-blocking position, said closure member slot limiting the opening movement of said closure member through abutment of its lower end with 20 said lever and the staple driving movement of said lever adapted to move said closure member to its closed position.
